UNITED STATES PATENT OFFICE.

CHRISTIAN AALBORG, OF WILKINSBURG, PENNSYLVANIA, ASSIGNOR, BY MESNE ASSIGNMENTS, TO WESTINGHOUSE ELECTRIC & MANUFACTURING COMPANY, OF EAST PITTSBURGH, PENNSYLVANIA, A CORPORATION OF PENNSYLVANIA.

CIRCUIT-INTERRUPTER.

1,121,574.

Specification of Letters Patent. Patented Dec. 15, 1914.

Application filed October 7, 1903. Serial No. 456,580.

To all whom it may concern:

Be it known that I, CHRISTIAN AALBORG, a citizen of the United States, and a resident of Wilkinsburg, in the county of Allegheny and State of Pennsylvania, have invented a new and useful Improvement in Circuit-Interrupters, of which the following is a specification.

My invention relates to circuit interrupters, and it has for its object to provide a device of the class above indicated that shall be specially adapted for interrupting high-voltage alternating current circuits.

Well known types of oil switches have usually been employed for interrupting high-voltage circuits. These devices comprise, in general, pairs of stationary contact members and movable bridging contact members which may be moved into and out of engagement with the stationary members, all of the contact members being immersed in oil or in some other suitable insulating fluid. In such devices it is practically impossible to operate the movable contact members to interrupt the circuits in less than approximately a twenty-fifth of a second, and since, at the frequencies usually employed, a complete cycle is accomplished in from one-sixtieth to one-twenty-fifth of a second, the current traversing the circuit would reach a maximum at least once, and probably twice, during the opening of the interrupter. Consequently, under the conditions indicated above, the interrupter must be capable of interrupting the circuit when a maximum current is flowing in it.

According to my present invention, I provide a plurality of stationary contact members, a single movable contact-bearing member which corresponds to the usual movable bridging member, referred to above, and a plurality of coöperating movable contact members which are so arranged as to be successively disengaged from the stationary members when the interrupter is actuated to break the circuit and the movable contact-bearing member is separated from the stationary members. In this way, a succession of breaks is provided, in place of the single circuit interruption of the prior art, which is of advantage, for the following reasons: The breaks are connected in series so that the arc must be sustained not only at the contact members first separated, but addi-

tional arcs in series with the first must be established at new points in the oil or other surrounding medium.

It is a well known fact that when an arc is once established in oil or air, the insulating properties of the medium immediately around the arc are impoverished and, consequently, a material advantage is gained by breaking the circuit established through the first arc in another place where the insulating properties of the medium are unimpaired.

In addition to the foregoing, by providing the succession of breaks referred to, the total time required to operate the movable member, which is approximately a twenty-fifth of a second, is divided into as many intervals as there are sets of stationary and movable contact members in the series. By utilizing a considerable number of contact members, one of the breaks must obviously occur at or near the zero point in the alternating current wave, and, when this point is reached in the succession of interruptions, the arc or arcs which may have been formed will immediately be quenched.

Figures 1 and 2 of the accompanying drawings are elevations, at right angles to each other, of a circuit interrupter, constructed in accordance with my invention, the inclosing casing being broken away to disclose the operating parts. Fig. 3 is a diagrammatic view of one complete cycle of an alternating current wave.

Referring to the drawings, the device illustrated in Figs. 1 and 2 comprises a fluid-containing tank or casing 1, a pair of stationary terminal members 2 and 3 which project through the cover 4 of the tank or casing and are supported thereby, a cross strip or support 5 of insulating material secured to the inner ends of the terminal members in a horizontal plane, a plurality of stationary contact terminals 6 to 17 secured to said strips, a movable contact bearing member 18, a plurality of coöperating contact terminals 19 to 30 secured thereto, an operating mechanism 31, and a vertical rod or shaft 32 which connects the contact-bearing member 18 to the operating mechanism.

The stationary contact terminals 6 and 17 are respectively connected to the circuit conductors 33 which extend through bushings 34, and a coöperating pair of contact ter-

minals 19 and 30 are secured to the movable contact-bearing member 18 and are adapted to be simultaneously separated from said stationary contact terminals 6 and 17. The 5 remainder of the stationary contact terminals 7 to 15 are rigidly secured to the cross strip 5 of insulating material between the stationary contact terminals 6 and 17, and a series of movable contact terminals 20 to 29, which coöperate therewith, are resiliently supported by the movable contact-bearing member 18.

Each of the movable terminals 20 to 29 is provided with a shank 35, which projects 15 through a suitable hole 36 in the contact-bearing member 18 and a nut 37, or other enlargement, is provided at the end of the shank in order to limit the independent movement between the contact terminal and 20 the said member 18, a helical spring 38 being coiled about the shank between the contact end of the terminal and the bottom of a recess 39 in which it operates. The movable contact terminals are arranged in a 25 series in which the independent movement of each successive member is greater than that of the preceding member.

The stationary and movable contact terminals are electrically connected so that the 30 line current, which is normally established, when the interrupter is closed, from stationary contact terminal 6 through a shunt connection 40 and contact terminals 19 and 30 to the other stationary contact terminal 17, 35 is completed back and forth through the entire series of contact terminals which are connected in pairs as soon as the movable contact terminals 19 and 30 are separated from the main stationary contact terminals 40 6 and 17.

I deem it unnecessary to describe the operating and tripping mechanism of the circuit interrupter since any devices may be employed in this connection which may be 45 found suitable for performing the desired functions.

The operation of the device is as follows: Assuming that alternating current is traversing the circuit interrupter, which occurs 50 its closed position, and that it is desired to interrupt the circuit; if the current wave is represented by the curve shown in Fig. 3 and the operating mechanism is actuated when the instantaneous current value is represented by the point *x* on the curve, the movable member of the interrupter will be completely separated electrically from the stationary member when the instantaneous current value is indicated by the point *C*. 55 The movable contact terminals 19 and 30 will be first separated from the main contact terminals 6 and 17, an arc obviously being established on account of the instantaneous current value which is assumed. A 60 very short interval after the separation of

the aforesaid contact terminals, contact terminal 20 will be separated from contact terminal 7, the instantaneous current value being represented by point *a*. The successive breaks occurring at the points *b*, *c*, *d*, *e*, *f*, *g*, 70 *h*, *i* and *j* on the curve, and, since point *c* is at or close to the zero point on the instantaneous current curve, the electric arc which was established when the main contact terminals were separated will be quenched 75 when the contact terminal 22 is separated from the contact terminal 9.

It will be readily understood that the number of separable contact terminals is sufficient to insure a substantial coincidence of 80 one of the breaks with a zero point in the current curve, whatever may be the point in the curve which corresponds to the initial break, and, consequently, the circuit will always be interrupted under the most favorable conditions.

Since various modifications in size and arrangement of parts may be effected within the spirit and scope of my invention, I desire that only such limitations shall be imposed as are indicated in the appended claims.

I claim as my invention:

1. In a circuit interrupter, the combination with a set of insulated stationary contact terminals electrically connected in pairs and disposed between the terminals of an interrupted service conductor, of a set of coöperating insulated movable contact terminals also electrically connected in 100 pairs in alternation with reference to the stationary contact terminals, and means for effecting successive disengagement of said movable contact terminals from the stationary contact terminals to open the circuit. 105

2. In a circuit interrupter, the combination with a set of insulated stationary contact terminals electrically connected in pairs and disposed between the terminals of an interrupted conductor of an alternating current circuit, a movable supporting member, and a set of coöperating contact terminals independently supported by said member and electrically connected in pairs in alternation with reference to the stationary contact terminals, and means for effecting successive disengagement of the movably supported contact terminals from the stationary contact terminals as said member is moved away from its circuit-closing position. 110 115 120

3. In a circuit interrupter, the combination with a set of stationary contact terminals electrically connected in pairs, of a set of movable contact terminals electrically connected in pairs and so disposed that the contact terminals of each pair coöperate with stationary contact terminals of different pairs, and means for causing said movable contact terminals to successively move 125 130

- out of engagement with the stationary contact terminals as the interrupter is opened.
4. In a circuit interrupter, the combination with coöperating sets of movable and stationary contact terminals which are electrically connected in pairs to produce a series of successive interruptions of a service conductor when separated, and means for completing a single low-resistance shunt circuit around all but the end terminals of the sets when the interrupter is closed.
5. In a circuit interrupter, the combination with a fluid-containing tank or casing, a cover therefor, and stationary terminal bushings projecting through and supported by the cover, of a horizontal strip or bar of insulating material supported within the casing from the inner ends of the bushings, a plurality of stationary contact terminals secured to said bar and electrically connected in pairs, a movable contact-bearing member and a series of coöperating movable contact terminals also electrically connected in pairs and having re-
- silient connections to said contact-bearing member.
6. In a circuit interrupter, the combination with a fluid-containing tank or casing, a cover therefor, and stationary terminal bushings projecting through and supported by the cover, of a horizontal strip or bar of insulating material supported within the casing from the inner ends of the bushings, a plurality of stationary contact terminals secured to said bar, a movable contact-bearing member and a series of coöperating movable contact terminals resiliently secured to said contact-bearing member by unequal lost-motion connections to permit unequal independent movements of said members.
- In testimony whereof, I have hereunto subscribed my name this 21st day of Sept., 1908.
